UNITED STATES PATENT OFFICE

2,078,347

SUCTION VALVE

Milton S. Shepherd and Francis C. Wiley, Salt Lake City, Utah, assignors of one-third to Louis A. Roser, Salt Lake City, Utah

Original application February 23, 1932, Serial No. 594,443. Divided and this application November 8, 1934, Serial No. 752,068

3 Claims. (Cl. 230—221)

Our invention relates to compressors and has for its object to provide a new and efficient fluid compressor for use primarily in refrigeration machines.

5 A further object is to provide a compressor which has a new type of noiseless suction valve and which valve is more efficient than those heretofore, giving greater compressibility to any type of compressor when used therein.

10 A still further object is to provide a simplified construction of suction valve in which air cushions and air pressure are used to stabilize the operation of the valve and to make it noiseless in operation.

15 A still further object is to provide a construction of intake or suction valve which is so built as to have longer life and to prevent "pounding off" of the lock nut thereon.

20 A still further object is to provide a compressor which has the suction valve so constructed that when starting, no load is carried until the compressor has attained sufficient speed to close the suction valve in the piston.

25 These objects we accomplish with the device illustrated in the accompanying drawing in which similar numerals and letters of reference indicate like parts throughout the several views and as described in the specification forming a part of this application and pointed out in the appended claims.

30 This application is a division of our former application filed Feb. 23, 1932, Serial Number 594,443, now Patent No. 1,985,481, of Dec. 25th, 1934, for Compressors.

35 In the drawing in which we have shown the best and most preferred manner of building our invention,

40 Figure 1 is a vertical diametrical section of a compressor piston and cylinder with our suction valve used in the piston head.

Figure 2 is a vertical diametrical section through the suction valve and cage removed from the piston.

45 Figure 3 is a section of the valve cage.

Figure 4 is a side elevation of the valve cage and valve.

50 Figure 5 is a plan view of Figure 3.

Figure 6 is an enlarged section of one edge of the valve and valve seat to show the double converging angle formed in both the valve and seat.

55 In the drawing we have shown the cylinder as A, the piston as B, and the suction or intake valve as D.

The suction valve D is carried in a cage 25

which cage is cylindrical in form with a valve seat formed in the top end in which the valve D is normally held away from its seat by the spring D1. The cage 25 is provided with a flange 26 therearound adapted to fit into a socket 27 in the piston head B, and be secured therein by placing an annular ring 28 thereabove resting on the flange 26 and fitting into an annular step 29 in the piston head. The ring is secured by spaced apart tap screws 30.

10 The bottom end of the cage 25 is formed as an inverted frustum of a cone and the center is bored out to leave an inverted frusto-conical chamber 31 therein and a vertical frusto-conical valve stem support bearing 32 is formed concentric within the inverted frusto-conical chamber 31 to support the valve stem D2. The bottom end of the frusto-conical portion of the cage 25 is bored concentric therewith to form a cylinder 33 in which a piston 34 is carried and operated. A central bore 35 is provided up through the center of the entire cage, and center support bearing 32, in which the valve stem of the valve D is carried, and the lower end of the stem D2 extends down through this bore 35 into the cylinder 33 and passes through a center threaded hole in the piston 34. A pin 36 secures the piston 34 onto the lower end of the stem D2. Thus the operations of the valve D are controlled by the retarded action of the piston 30 in the cylinder.

15 A small relief port 37 is bored into the cylinder 33 through the side wall of the cage 25 into the cylinder 33 near the top end thereof. The relief port is to allow air to be forced from the cylinder when the valve is opening, but the port 37 is bored into the chamber a short distance from the end thereof so that the piston when rising in the cylinder moves freely until just before it reaches the end of its stroke 20 and the end of the stroke will be cushioned by the compression of the air in the chamber 37 above the piston 32. The top inner edge of the bearing block 32 is inwardly chamfered at 38 to provide an oil retaining well to catch and retain oil for lubrication of the valve stem. Ports 39 through the side walls of the cage 25 provide air passage thereinto from the space surrounding the piston into the cylinder A.

25 The valve D and its seat 40 are each cut with 50 their faces made of two angled chamfers so that they will seat more closely than possible with one single chamfer. The two chamfers in the head are shown as 41 and 42 and those in the seat as 43 and 44. These two sets of chamfers fit 55

into each other when the valve is resting in its seat thereby providing a perfect non-leaking valve. The valve spring **D1** is carried in the chamber **31** surrounding the base of the frustum **32**, and engaging the bottom of the valve **D**.

The piston **B** of the device is of the usual compressor type having a head and skirt joined together by vertical struts leaving an air space between the skirt and head which space is joined 10 into the circuit of the system in which the compressor is being used or to the atmosphere if air is being compressed.

Having thus described our invention we desire to secure by Letters Patent and claim:

15 1. In a compressor suction valve, the combination of a piston; a valve cage carried therein; a ring to secure the cage to the piston; a suction valve mounted in the head of the cage with the face of the valve and the face of the valve seat formed with two converging angles; a small cushioning cylinder formed in the bottom end of the frusto-conical lower end of the valve case; a small piston carried in said cushioning cylinder with the stem of the suction valve secured through said 20 small piston; an escape port through the cage near the top end of the small cushioning cylinder to allow for closing of the valve against air suction and pressure and affording a quick operating valve; and a spring carried in said cage engaging the 25 cage and valve to normally hold the valve slightly away from its seat.

2. A suction valve for compressors, comprising a step cut cage adapted to fit into the piston head of the compressor; a frusto-conical cage depending therefrom having a cylinder in the bottom end thereof; a central upwardly extending frusto-conical valve stem guide formed within said cage; openings through the wall of the frusto-conical depending cage to allow fluid to pass into the 30 valve chamber which is formed within the cage; a valve seat formed in the head of the cage having the seat of two angled chamfers joined medi-

ally of the seat; a valve carried in said cage having the face formed of like angled chamfers to fit the valve seat and having the stem depending through the valve stem guide; a piston secured onto the lower end of the valve stem to operate within said cylinder in the bottom of the cage; a spring to normally hold the valve spaced from the valve seat, but of a tension to allow the valve to seat when the piston is operating at sufficient speed to close the valve and compress the fluids thereover; and a bleeder hole through the cage into the cylinder near the top end thereof to dampen the movements of the valve but to prevent pressure locking of the valve.

3. In a compressor valve of the type described, 15 the combination of a cylinder having a compression piston operable therein, said piston having a step cut opening medially therethrough; a valve cage having a step cut flange around the perimeter thereof fitting into the step cut in the piston and a depending frusto-conical body below said flange; an annular ring secured above the flange and to the piston to hold the cage within the piston; a frusto-conical opening in said cage with the top edge chamfered to form the valve 20 seat; a frusto-conical valve stem guide formed within the opening in the cage to guide the valve and having the top end of the guide chamfered inwardly to catch oil for lubricating the valve stem; a small cushion cylinder formed in the 25 bottom end of the cage; a valve carried through a central bore in said cage and guide with the valve to seat in the valve seat formed in the top of the cage when compressing; a spring carried in the opening in the cage to normally hold the 30 valve from its seat; and a small piston carried in said cushion cylinder in the bottom of the cage with the valve stem secured to the piston to retard the closing and opening of the valve.
